UNITED STATES PATENT OFFICE.

OZRO N. WISWELL, OF SNOQUALMIE, WASHINGTON.

ELECTRICAL SWITCH.

1,076,528.

Specification of Letters Patent.

Patented Oct. 7, 1913.

Application filed July 12, 1911. Serial No. 686,318.

To all where it may concern:

Be it known that I, Ozro N. Wiswell, a citizen of the United States, and resident of the town of Snoqualmie, in the county of King and State of Washington, have invented certain new and useful Improvements in Electrical Switches, of which the following is a specification.

My invention relates to improvements in electrical switches, particularly to the construction of the jaws which form one terminal of said switches.

My invention comprises the novel parts and combinations of parts which will be hereinafter described and particularly pointed out in the claims.

The object of my invention is to provide a better construction of the jaws for electrical switches, such that a better and more continuously equal spring contact may be obtained between the jaws and the switch bar in all positions, and the switch be therefore more effective for the conveyance of the electrical current.

My object is further to improve and simplify such parts.

In the accompanying drawings I have shown my invention embodied in the form which is now preferred by me.

Figure 1 is a plan view of the jaws in my preferred construction. Fig. 2 is an edge view or elevation of the same jaws, these being in the position assumed when the switch bar is not in place between the jaws. Fig. 3 is a view like Fig. 1 except that the jaws are in the position assumed when the switch bar is in place between them.

The type of switch used for illustrating my invention, is that in which two separated bars form one terminal and a movable bar, adapted to be moved between the bars forming said terminal, constitutes the complementary terminal. Such switches are ordinarily referred to as knife or jaw switches. My invention relates more particularly to the construction of the jaws, whereby they are enabled to make a better contact with the knife or swinging bar, in cases where they are not in exact relation thereto.

The switch as herein illustrated has a base 4 to which the bars or plates forming the jaws are secured. These plates 1 are secured, one at each side the base, and at their outer ends are bent outward, or away from each other, by a curve 10, so as to form a flaring mouth for the more certain guidance of the knife bar or swinging member of the switch when being inserted.

Secured to the outer ends of the plates 1 are plates 3, which are shaped substantially like the plates 1, but are enough shorter to not quite reach the base 4. These plates 1 and 3 are firmly secured together at their outer ends, as by rivets 6, the desire being to secure their adjacent or opposed faces closely together, so that, for all practical purposes, they will act as one piece through this short end section.

The outer plates 1 are preferably curved so as to tend to bend slightly inward as they extend away from the base, this curvature commencing near the base, as at 11. The plates 1 and 3 are curved with a slightly different curvature near the point 10, so that there is a tendency to a slight separation, as is shown in Fig. 2. Outside the plates or bars 1 may be placed supporting bars 2, which are secured to the base and have their outer ends separated slightly from the bars 1; this preferably being due to the initial curvature of the bars 1, the bars 3 being straight. These outer bars 2 may be omitted, particularly when the size and quality of material used in the bars 1 are such as to secure a satisfactory strength and resiliency in themselves.

In Fig. 2 I have shown the relative position of the knife bar or swinging member of the switch by dotted lines at 7, and the same in place between the jaws in Fig. 3.

The action between the two bars 1 and 3 is quite different from that between the two halves of a bar bent upon itself, but with its sides not contacting. In the latter construction the spring action is mainly confined to the bend joining the two parts, and the pressure upon the inserted blade varies with its distance from such bend, this pres-

sure decreasing as the distance from the bend increases.

The bars 1 and 3 being secured with their faces in actual contact, the knife bar 7 entering between the two halves of the switch, in bringing the bars 1 and 2 together into the position shown in Fig. 3, produces a result which may be described as rocking the bar 3 upon the bar 1, that is, the point of divergence from contact is transferred toward the base 4 as the knife bar 7 enters between the jaws of the switch.

The two bars 1 and 3 may be considered as levers having a measure of flexibility. 15 Their fulcrum point is the point of divergence from contact. As the knife bar 7 enters between the two bars 3, the bars 1 and 3 are bent and the point of contact travels backward toward the base. In consequence 20 the pressure of the spring against the knife bar is not being greatly reduced as it passes inward between the jaws. From this it results that there is a better electrical contact between the knife bar and the jaws. 25 The same rocking action, or transference of the fulcrum point between the supporting bar 2 and the spring bar 1 takes place as has been described as occurring between the bars 1 and 2. This results in a much more equal 30 pressure upon the knife bar at all points than if these members were all acting independently, without any effect upon each other.

If the knife bar 7 should happen to not be 35 parallel with the true planes of the jaws, the jaws are sufficiently flexible to adjust themselves to this and make a true and large contact in spite of the twist of the knife bar.

Securing the two bars 1 and 3 with their 40 faces in close and unyielding contact at their outer ends, is superior to an open bend, for many reasons. As above pointed out it results in a transference of the fulcrum point along the bars so as to keep this fulcrum point near the entering blade at all 45 times, thus making the pressure exerted by the bars upon the blade more nearly equal at all points. This produces a superior contact than would follow were the two bars 50 connected by an open bend, as in the latter case the pressure upon the blade would rapidly decrease as it passed inward between the jaws. Arcing, which always occurs to a greater or less extent upon opening and 55 closing a switch, always acts upon that portion where the make and break occurs. This is the outer end portions of the jaws, which portions, in the ordinary construction, form a part of the spring section and any deterioration 60 thereof in the way of reduction of area or loss of resiliency causes a direct loss in efficiency of the jaw. Such arcing is injurious to a switch in two ways; first, by actual burning away of the material of the

switch, thus reducing the cross section of the 65 arm. Second, by annealing the material of the switch and destroying its resilient qualities. As, in my construction, the point of arcing is confined to that portion in which the two parts of the jaw are secured with 70 their faces in contact, the material throughout the entire area affected by arcing, acts only as a physical or binding connection between the jaws and not at all as a spring. For this function its area is so great that a 75 large reduction in area would still leave it with ample strength. As to the effect of the annealing action, this will have no effect upon the spring action of the jaws, as the area affected in this way at no time acts as 80 a spring, this action being confined to the body of the jaws sufficiently removed from the arcing zone to be unaffected by the arcing.

What I claim as my invention is: 85

1. A jaw member for electrical switches comprising two spring-like members secured together at one end with their faces in contact, one of said members being secured at its opposite end to a support and the other 90 constituting the contact member, said members being differently curved to normally hold their major part separated, and adapted to have said normally-separated parts brought gradually into contact as the switch 95 passes over the contact member.

2. In an electric switch, in combination, a base, a pair of spring arms secured at one end to said base and projecting therefrom in the same direction but in separated relation, 100 a spring arm secured to and with a side surface in contact with the inner surface of the outer end of each of said first-mentioned arms, the arms so connected being given an initial curvature acting to separate them as 105 they extend away from their point of union when unrestrained but permitting bringing said surfaces into contact by the pressure of the movable member of the switch in closing.

3. A jaw member for electric switches 110 comprising two spring-like arms secured together at one end with side faces in close contact, the secured ends of said arms being curved to normally slightly diverge their free portions away from their secured ends, 115 the free end of one of said arms being longer than the other, and means for securing said extended end to a support.

4. In an electric switch, the combination with a base, of spring arms secured to the 120 base and projecting in the same direction from the base but in separated relation, guard bars secured to the base and extending outside of and alongside said spring arms and slightly diverging from the normal or 125 unrestrained position of the spring arms, a second pair of spring arms, each secured to the inner surface of the outer ends of the

first mentioned spring arms and extending backward therebetween, the connected spring arms being curved to normally diverge away from their point of connection, said inner 5 set of arms serving as the contact members of the complemental part of the switch. In testimony whereof I have hereunto af-

fixed my signature at Seattle, Washington, this 6th day of July, 1911.

O. N. WISWELL.
